vale, Pa., a corporation of Pennsylvania

Original application February 17, 1939, Serial No.
256,946. Divided and this application October
12, 1939, Serial No. 299,117

8 Claims. (Cl. 200—90)

My invention relates to coding apparatus, and particularly to coding apparatus comprising a code transmitter having contacts and means for periodically operating said contacts in a predetermined sequence.

5 The present application is a division of my copending application for Letters Patent, Serial No. 256,946, filed February 17, 1939, for Signal systems.

10 I shall describe one form of apparatus embodying my invention, and shall then point out the novel features thereof in claims.

Code signal systems using recurrent impulses of direct current have been proposed for railroads. Direct current from a convenient source such as a battery is periodically interrupted at different code frequencies or rates, code frequencies of 180, 120 and 75 cycles per minute being those generally used. The individual direct current impulses are of relatively high peak voltage and of a short duration. That is, the duration of the impulse is short as compared with the duration of the cycle period. For example, in the 120 code each code cycle period is of one-half second duration and the duration of an individual current impulse would preferably be of the order of one hundredth second. Impulses of such short duration serve to limit the output from the battery to a low energy level. In such signal systems a code following relay is operated by the coded current to a first position when current flows and to a second position when the current ceases. Hence the period the relay remains in the position effected by the presence of current ("on" period) is short as compared with the period the relay remains in the position ("off" period) effected by the absence of current because the impulses are of short duration as compared with the duration between successive impulses. The decoding apparatus governed by the code following relay for selectively controlling some signal device in accordance with the different codes is ordinarily of such construction that most satisfactory operation is obtained when 45 the code following relay is operated with substantially equal on and off periods.

Accordingly, a feature of my invention is the provision of novel and improved coding apparatus wherewith impulses of direct current corresponding to the different code frequencies or rates are supplied in such a manner that a code following relay operated thereby is operated with substantially equal "on" and "off" periods. Other features and advantages of my invention will appear as the specification progresses.

For a better understanding of my invention reference can be had to the accompanying drawing in which Fig. 1 is a view partly diagrammatic and partly in plan showing a coder or code transmitter embodying my invention. Fig. 2 is a detail of the coder of Fig. 1. Fig. 3 is a diagram illustrating the operation of certain circuit controlling contacts of the coder of Fig. 1. Fig. 4 is a diagram illustrating operating characteristics of the current impulses created by the coder of Fig. 1. In each of the several views like reference characters designate similar parts.

Code transmitters of the torsional type are well known. For example, the code transmitter of the general construction covered by the United States Letters Patent No. 1,858,876, granted May 17, 1932, to Paul N. Bossart for Coding apparatus, has been found satisfactory. My present invention is an improvement on code transmitters of the torsional type such as covered by the above Bossart Patent No. 1,858,876.

Referring to Fig. 1, a magnetic core structure 29 is mounted on a frame 30 of suitable non-magnetic material such as brass. The core 29 terminates in two spaced pole pieces 29a and 29b and has mounted thereon a winding 31. An armature 32 is secured to a shaft 33 in any convenient manner here shown as by set screw 32a in a hub of the armature. Shaft 33 is journaled in frame 30 so that the armature 32 is disposed for rotatable movement between the pole pieces 29a and 29b. The armature 32 is cylindrical in shape and is provided with an outer surface (see Fig. 2) so shaped that when the armature is rotated in a first direction (counterclockwise in Fig. 2) from a normal or biased position the air gaps between the outer surface of the armature and the pole pieces 29a and 29b are gradually decreased, but if the armature is rotated in the opposite or second direction (clockwise in Fig. 2) from such normal position the air gaps are at first gradually increased and then abruptly increased. The armature 32 is biased to its normal position by a spiral spring 34 the outer end of which is secured to the frame 30 by screws 35 and its inner end to the hub of armature 32 by screws 106. The coder is provided with a contact K1 for controlling the supply of current to winding 31 and which contact comprises a contact member 36 disposed for operation by rotation of shaft 33, and a stationary contact member 37, the arrangement being such that contact member 36 engages contact member 37 to close the contact K1 at the normal position of armature 32 and the contact member 36 moves out

of engagement with contact member 37 to open the contact K1 when the armature 32 swings in its first direction away from the normal position. The contact member 36 is connected with a terminal 38 through a suitable flexible connection 38a, while the contact member 37 is connected with one terminal of winding 31. When a source of direct current is connected at terminals B and C of Fig. 1, the winding 31 is energized and a magnetic flux is built up in the core 29 which attracts armature 32 against the force of the bias spring 34 in its first direction from its normal position, that is, armature 32 swings in the direction of the decreasing air gap. After a limited rotation of armature 32, the contact K1 is opened and the winding 31 is deenergized. Bias spring 34 now causes armature 32 to swing back toward its normal position and contact K1 is closed to again energize winding 31. Due to the inertia of the parts, armature 32 swings past the normal position in its second direction a limited distance before it is again rotated in its first direction due to the attraction created by the energization of winding 31. The parts are so constructed that armature 32 swings substantially equal distances each side of its normal position. It is clear that as long as the current source is connected at terminals B and C the armature 32 will oscillate at a frequency governed by the mass of the armature 32 and the stiffness of the spring 34. For example, the parts may be so proportioned and adjusted that armature 32 oscillates at the frequency of 180 cycles per minute or at the frequency of 120 cycles per minute or at the frequency of 75 cycles per minute.

A contact M4 is carried on shaft 33 by means of clips 39. Contact M4 is preferably of the liquid flow type such as a mercury switch, a common construction of which consists of a glass envelope having two spaced metal electrodes and a quantity of mercury sealed therein, the arrangement being such that the mercury bridges the electrodes at certain positions of the envelope and the mercury flows away from the electrodes when the envelope is tilted. In the embodiment here contemplated, contact M4 is so positioned on shaft 33 that the contact is closed at the normal position of the armature 32 and is tilted to open the contact as the armature swings in its first direction, and is reclosed as the armature swings back to its normal position and remains closed while the armature swings in its second direction. Hence, as illustrated in Fig. 3, where the black area represents the closed position of the contacts, contact M4 opens at the start of each operating cycle of the coder (armature starts to swing in said one direction), is reclosed at the end of the first half period of the cycle (armature returned to normal position) and remains closed during the second half period of each operating cycle (armature swings in said second direction and returns to normal position).

Again referring to Fig. 1, a second armature 40 is fixed on a hollow shaft 47 which is slipped over and rotates freely on shaft 33. Armature 40 is joined to the shaft 33 through a spiral spring 41, the outer end of spring 41 being secured to armature 40 through an L-shaped member 42 bolted to armature 40 at 43 and secured to the spring 41 at 44. The inner end of spring 41 is secured to a sleeve 45, which sleeve is in turn secured to the shaft 33 by a set screw 46. As here shown, three contacts M1, M2 and M3

are mounted on the hollow shaft 47 through the medium of suitable clips 48. Contacts M1, M2 and M3 are preferably of the liquid flow type similar to contact M4. An electromagnet 49 normally energized by any convenient source of current such as a battery 50 dampens the motion of armature 40 by induction with the outer rim 40a of the armature 40, the outer rim of the armature passing between spaced pole pieces of magnet 49, as will be readily understood by an inspection of Fig. 1.

It is clear that when armature 32 is oscillated the hollow shaft 47 and armature 40 are also oscillated because of the connection effected by spring 41. The motion of armature 40 lags the motion of shaft 33 and armature 32 by an amount depending upon the mass of armature 40, the stiffness of spring 41 and to a small extent by the damping of magnet 49. If spring 41 is a stiff spring, armature 40 will lag only a few degrees behind armature 32. If spring 41 is weak, the lag of armature 40 becomes greater. The actual amount of lag can be readily controlled by adjusting the stiffness of spring 41. Magnet 49 produces damping which increases with increasing velocity of armature 40, the latter damping being desirable to prevent the amplitude of the oscillation of armature 40 from becoming too great. It is obvious that the magnetic damping produced by magnet 49 can be replaced by vanes mounted on the outer rim of armature 40 to increase its air resistance.

As illustrated in Fig. 3, contacts M1, M2 and M3 of the present embodiment of the invention are mounted in a position so that contacts M1 and M2 are closed and contact M3 is open at the start of each operating cycle, that is, at the normal position of the armature 32. As armature 32 swings in its first direction away from the normal position, contact M1 is tilted to open at a predetermined point. At a predetermined interval after contact M1 is opened, contact M2 is tilted to close, and then still later contact M3 is tilted to open. As armature 32 swings back to its normal position to complete the first half or "on" period of the cycle and then swings in its second direction, the contacts M3 and M1 are not reclosed and contact M2 is not again opened until predetermined positions are reached in the second half period of the operating cycle of the armature 32 because of the lag of armature 40. I have found that with the construction described above contacts M1, M2 and M3 can be made to accurately and reliably open and close at selected positions in the operating cycle of the coder.

It is clear that with contacts M1, M2, M3 and M4 operated during each operating cycle of the coder in the predetermined sequence pointed out above, circuits can be controlled in such a manner as to provide impulses of current at predetermined points of the operating cycle. It is also obvious that a coder constructed in accordance with my invention permits almost any desired sequence in the operation of a plurality of contacts to be effected.

The utility of coding apparatus which includes contacts and means for operating the contacts in a preselected manner is fully explained in my aforementioned copending application Serial No. 256,946 of which the instant case is a division. It is sufficient for the present case to point out that with contacts M4 and M3 closed circuits are completed for connecting a battery to the primary winding of a first and a second trans-

former, respectively, and magnetic energy is built up in such transformer, the time constant of the circuits being preferably such that energy builds up relatively slow and little if any energy is inductively transferred to the secondary winding of the respective transformer. Contact **M1** completes a first circuit connection for the secondary winding of the first transformer to a transmitting circuit such, for example, as a track circuit, and contact **M2** completes a second connection for the secondary winding of the second transformer with such track circuit. Looking at Fig. 3, it follows that at the start of an operating cycle energy is stored in the magnetic circuits of the first and second transformers because both contacts **M3** and **M4** are closed. Also, the secondary winding of the first transformer is connected with the track circuit because contact **M1** is closed, but the secondary winding of the second transformer is disconnected from the track circuit because contact **M2** is open. Just after the start of an operating cycle, contact **M4** is opened, interrupting the circuit to the primary winding of the first transformer and the energy stored in the first transformer dies away, the decay being rapid and an electromotive force of relatively high peak voltage induced in the secondary winding of the first transformer so that a current impulse of corresponding magnitude is supplied to the track circuit. This current impulse may be of only one-half cycle duration or it may have a damped wave form because of the oscillatory nature of the track circuit. The important feature of such impulse, as far as my present invention is concerned, is the fact that the impulse occurs at substantially the start of the operating cycle. That is to say, the impulse occurs at a preselected point of the operating cycle. Just after the first impulse ceases, contact **M1** opens to disconnect the secondary winding of the first transformer from the track circuit and shortly thereafter contact **M2** closes to complete the circuit of the secondary winding of the second transformer with the track circuit. At a predetermined later point of the first half period ("on" period) of the operating cycle, contact **M3** is opened to interrupt the circuit to the primary winding of the second transformer and the energy stored in that transformer dies away rapidly to induce an electromotive force in the secondary winding of the second transformer so that a second current impulse is supplied to the track circuit, such second current impulse being similar to the first impulse. Consequently, as illustrated in Fig. 4, two current impulses are supplied to the track circuit during the on period of each operating cycle of the coder. These two current impulses occur at points of the first half period of the operating cycle predetermined by the setting of the contacts **M1**, **M2**, **M3** and **M4**. In other words, the two current impulses are spaced apart at a predetermined time interval by the setting of the contacts of the coder.

The code following relay receiving energy from such track circuit is therefore supplied with two energizing impulses each on period of the code cycle. It is clear that by proper spacing of the two current impulses the energization of the relay effected by the second impulse occurs just as the energization effected by the first impulse begins to die away, with the result that the relay is retained at the position corresponding to that effected by the presence of current for substantially the full first half period of the operating

cycle. Hence, the code following relay is operated with substantially equal on and off periods because of the spacing of the two current impulses during the on period of the code cycle.

If the coder is to be used in a circuit supplying impulses of the 75 code rate the setting of the contacts would be such that the two current impulses are spaced slightly further apart than would be the case when the coder is used with a circuit supplying current impulses of the 120 code rate.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In a code transmitter having an armature fixed on a shaft for rotation and biased by spring means to a normal position about which it oscillates at a pre-selected frequency when the magnet of the code transmitter is supplied with current over a circuit including a contact operated by movement of the armature in a predetermined direction away from said normal position, the combination comprising, a member mounted in axial alignment with said shaft for rotation, resilient means to connect said member with said shaft to cause said member to oscillate with said armature with a predetermined lag, a first coding contact mounted for operation by said armature and shaft, and a second coding contact mounted for operation by said member, a predetermined time interval after said first coding contact is operated.

2. In a code transmitter having an armature fixed on a shaft for rotation and biased by spring means to a normal position about which it oscillates at a preselected operating cycle when the magnet of the code transmitter is supplied with current over a circuit including a contact operated by movement of the armature in a predetermined direction away from said normal position, the combination comprising, a member mounted in axial alignment with said shaft for rotation, means including a spiral spring to connect said member with said shaft to cause said member to oscillate at said operating cycle with said member lagging said armature in a predetermined manner, a first coding contact operated by said armature at a preselected point of the operating cycle, and a second coding contact operated by said member at another preselected point of the operating cycle.

3. In a code transmitter having an armature fixed on a first shaft for rotation and biased by spring means to a normal position about which it oscillates at a preselected operating cycle when the magnet of the code transmitter is supplied with current over a circuit including a contact operated by movement of the armature in a predetermined direction away from said normal position, the combination comprising, a hollow shaft adaptable of loose mounting on said first shaft, means including a spiral spring to connect said hollow shaft with said first shaft to cause said hollow shaft to oscillate at said operating cycle with a predetermined lag with respect to said armature, and a coding contact operated by said hollow shaft at a preselected point in the operating cycle.

4. In a code transmitter having a first armature fixed on a first shaft for rotation and biased

- by spring means to a normal position about which it oscillates at a preselected frequency when the magnet of the code transmitter is supplied with current over a circuit including a contact operated by movement of said armature in a predetermined direction away from said normal position, the combination comprising, a hollow shaft adaptable of loose mounting on said first shaft, a second armature fixed on said hollow shaft, means including a spring to connect said hollow shaft with said first shaft to cause said hollow shaft and second armature to oscillate when said first armature is oscillated with said hollow shaft and second armature lagging said first armature, means mounted for magnetic relationship with said second armature to control in part the lagging of said hollow shaft and second armature, and a coding contact operated by the movement of said hollow shaft and second armature.
5. In a code transmitter having a first armature fixed on a first shaft for rotation and biased by spring means to a normal position about which it oscillates at a preselected operating cycle when the magnet of the code transmitter is supplied with current over a circuit including a contact operated by movement of said armature in a predetermined direction away from said normal position, the combination comprising, a hollow shaft adaptable of loose mounting on said first shaft, a second armature fixed on said hollow shaft, resilient means to connect said hollow shaft with said first shaft to cause said hollow shaft and second armature to oscillate at said preselected operating cycle with said hollow shaft and second armature lagging said first armature, means mounted for magnetic relationship with said second armature to control in part the lagging of said hollow shaft and second armature, a first coding contact operated by said first armature at a preselected point of the operating cycle, and a second coding contact operated by said hollow shaft and second armature at another preselected point of the operating cycle.
6. In combination, a magnet having a winding and two spaced poles, a cylindrical armature fixed on a first shaft and mounted for rotation between said poles, spring means to bias said armature to a normal position, a contact mounted on said shaft normally closed and adaptable of being opened when said armature rotates in a predetermined direction from said normal position, means including said contact for supplying current to said winding to cause said armature to oscillate at a frequency predetermined by its mass and by the stiffness of said spring means, a hollow shaft adaptable of loose mounting on said first shaft, means including a spring to connect said hollow shaft with said first shaft to cause said hollow shaft to oscillate with said armature with a predetermined lag, and another contact operated by said hollow shaft.
7. In combination, a magnet having a winding and two spaced poles, a first cylindrical armature fixed on a first shaft and mounted for rotation between said poles, spring means to bias said armature to a predetermined normal position, a contact controlled by said armature and adaptable of being opened when said armature oscillates in a predetermined direction from said normal position, means controlled by said contact for energizing said winding to cause said armature to oscillate at a frequency predetermined by its mass and the resiliency of said spring means, a hollow shaft adaptable of being slipped over said first shaft, a second cylindrical armature fixed on said hollow shaft, means including a spiral spring to connect said second armature with said first shaft to cause said second armature and hollow shaft to oscillate when said first armature is oscillated with said second armature and hollow shaft lagging said first armature a predetermined degree, another contact operated by said hollow shaft, and magnetic means to control in part the lagging of said second armature.
8. In combination, a first armature fixed on a first shaft for rotation, spring means to bias said armature to a predetermined normal position, motor means to operate said armature in a given direction, circuit means including a contact operated by movement of said armature to cause said armature to oscillate at a frequency predetermined by the mass of the armature and resiliency of said spring means, a hollow shaft adaptable of being slipped over said first shaft, a second armature fixed on said hollow shaft, means including a spiral spring to connect said second armature to said first shaft to cause said hollow shaft and second armature to oscillate at said predetermined frequency when said first armature is oscillated with a lag predetermined by the resiliency of said spiral spring, magnetic means mounted for magnetic relationship with said second armature to dampen the movement of said second armature and first and second coding contacts mounted on said first and hollow shafts respectively for operation a predetermined time interval apart.

WILLARD P. PLACE.
